UNITED STATES PATENT OFFICE.

EDWIN D. COLLINS, OF BEECHWOOD, NEW JERSEY, ASSIGNOR TO SUMMIT THREAD COMPANY, OF EAST HAMPTON, CONNECTICUT, A CORPORATION OF MAINE.

SEWING-MACHINE SHUTTLE.

Application filed February 11, 1922. Serial No. 535,723.

To all whom it may concern:

Be it known that I, EDWIN D. COLLINS, a citizen of the United States, residing at Beechwood, in the State of New Jersey, have invented new and useful Improvements in Sewing-Machine Shuttles, of which the following is a specification.

This invention relates to a rotary shuttle of the Willcox & Gibbs type, comprising a circular wall forming a bobbin-chamber adapted to contain a universally-wound bobbin, a fixed cross-bar extending across the inner end of the chamber, a fixed tubular post on the cross-bar centrally located in the chamber, an externally polygonal bobbin core-engaging sleeve mounted to rotate on the post, and means associated with the post and sleeve for confining the sleeve against free removal from the post, so that the bobbin core may be removed from the sleeve without removing the sleeve from the post.

The polygonal perimeter of the sleeve presents salient angles, adapted to bear on the internal surface of the cylindrical paper tube forming the core of a universally-wound bobbin. There is usually a slight variation in the internal diameter of the cores of different bobbins, so that while the salient angles of the sleeve are adapted to indent a core of minimum diameter, and prevent loose or accidental removal of the core from the sleeve when the shuttle is being manipulated, while disconnected from the sewing-machine, a core of larger internal diameter is so loosely engaged with the sleeve that it is liable to slip from the post when the latter is inverted. This liability involves loss of time in recovering a bobbin whose core is accidentally removed from the sleeve.

The object of the invention is to enable the polygonal sleeve to so engage bobbin cores of different internal diameters, as to prevent liability of the accidental removal of the core, and the thread winding thereon, from the sleeve.

The invention consists in the improved form of the sleeve hereinafter described and claimed.

50 Of the accompanying drawings forming a part of this specification,—

Figure 1 is a plan view, on an enlarged scale, of a shuttle having a sleeve embodying the invention, and of a bobbin engaged with the sleeve.

Figure 2 is a section on line 2—2 of Figure 1.

Figure 2^a is a view similar to Figure 2, certain parts shown by Figure 2 being omitted.

60 Figure 3 is a perspective view, showing the sleeve on a larger scale.

Figures 4 and 5 are side views of parts shown by Figure 2, separated from the shuttle.

65 The same reference characters indicate the same parts in all of the figures.

12 represents the circular wall of a rotary Willcox & Gibbs shuttle, said wall forming a chamber adapted to contain the tubular 70 paper core 13 and thread winding 14 constituting a universally-wound bobbin of well known form. 15 represents a cross-bar fixed to the wall and extending across one end of the chamber, said cross-bar supporting a 75 tubular post 16. 17 represents an externally polygonal sleeve mounted to rotate on the base portion of the post, and provided with salient angles 17^a adapted to bear on the internal surface of the core 13. The post 80 is provided with the usual means for preventing loose removal of the sleeve 17 from the post, said means being embodied as follows:

85 The sleeve is provided near its outer end with an inwardly projecting annular flange 19, one side of which forms a seat for the head 20 of a tubular stud 21, which is split longitudinally at one side, as shown at 22. The stud has a close fit in the bore of the 90 post 16, and has an internally threaded bore with which is engaged a screw 23 having a tapered head 24. After the sleeve is placed on the post, the stud 21 is inserted in the opening surrounded by the sleeve 95 flange 19, and the screw 23 is screwed into the threaded bore of the stud until its head 24 expands the split stud into a firm binding engagement with the bore of the post 16, the stud being thus confined so that its head 20 prevents removal of the sleeve from the post, the sleeve being at the same time free 100 to rotate on the post. Undesirably loose and free rotation of the sleeve on the post is prevented by the cooperation of a spring 105 26 with the stud head 20, and with the sleeve flange 19, said spring surrounding a reduced portion of the post and acting to press the sleeve flange 19 against the stud head 20.

The construction thus far described, in- 110

cluding the structural features shown by the drawing and not described, is well known.

In carrying out my invention, I provide the sleeve 17 with serrations 27, so arranged as to indent portions of the internal surface of the bobbin core 13, and compensate for variations in the internal diameters of different cores, and prevent liability of the accidental removal of any core and its thread winding from the sleeve.

The serrations are arranged to project outward from salient angles 17^a of the sleeve, and may be formed by the impact of a sharp-edged tool against said angles, the tool being so formed and directed that its impact displaces portions of the metal of the sleeve and forms serrations or barbs offering more resistance to the removal of the core from the sleeve, than to its application to the sleeve.

I prefer to locate the serrations at the inner end portion of the sleeve and in groups of two or more, three being the preferred number. I also prefer to serrate or barb

each alternate angle 17^a, leaving the others plain, as indicated by Figure 3.

I claim:

A sewing machine shuttle comprising a bobbin chamber, a fixed cross-bar extending across the inner end of the chamber, a fixed tubular post on said cross-bar centrally located in said chamber, an externally polygonal bobbin-core-engaging sleeve, mounted to rotate on said post, and adapted to bear on the internal surface of a bobbin core, salient angles of the sleeve being provided with barbs projecting outward from the sleeve and adapted to permit a bobbin to be readily positioned on the sleeve and to indent the core and resist removal thereof, and means associated with the post and sleeve for confining the sleeve against free removal from the post and for frictionally retarding rotation of the sleeve and a bobbin engaged therewith.

In testimony whereof I have affixed my signature.

EDWIN D. COLLINS.
